J. T. McCABE,
DOOR HANGER.
APPLICATION FILED APR. 18, 1913.

1,082,129.

Patented Dec. 23, 1913.

UNITED STATES PATENT OFFICE.

JAMES T. McCABE, OF NEW YORK, N. Y.

DOOR-HANGER.

1,082,129.

Specification of Letters Patent.

Patented Dec. 23, 1913.

Application filed April 18, 1913. Serial No. 762,047.

To all whom it may concern:

Be it known that I, JAMES T. McCABE, a citizen of the United States of America, and a resident of the borough of Manhattan, city, county, and State of New York, have invented certain new and useful Improvements in Door-Hangers, of which the following is a specification.

My invention relates to door hangers, and especially to hangers for that type of doors which are composed of two parts movable relatively to each other and conjointly closing a door-opening. In this type of doors, it has been heretofore proposed to connect the rider bars of the separate halves of the door together through the instrumentality of a pinion mounted upon the rider bar of one half and gearing into a rack upon the rider bar of the other half, and also into a rack fixed in the door opening whereby the movement of the door half on which the pinion is mounted produces a movement of the other half of the door, of double the speed, or vice versa. In such a construction it has been found difficult to preserve under the conditions of settlement and wear, and under the necessary adjustments which must be made of the rider bars vertically, the proper engagement of the pinion with the two racks, and for the purpose of over-coming these defects my invention consists in mounting the pinion upon its rider bar, not on a fixed pivot, as has heretofore been the case; but in such a manner that the pinion is capable of movement in respect to the usual adjustments of rider bars, thereby permitting a wider range of adjustment of the door halves and the rider bars thereof without disturbing the proper meshing of the pinion than is possible with the present construction.

Referring to the accompanying drawings in which corresponding parts are designated by corresponding marks of reference, Figure 1 is a perspective view of a structure embodying my invention. Fig. 2 is a vertical cross section thereof, and Fig. 3 is a diagrammatic side elevation.

The two halves A and A' of the door are of the usual construction and each is hung from a rider bar B, B', respectively, which rider bars are of a like construction with each other, but are reversely arranged.

Above the door opening is the angle bracket C, which carries the stationary tracks D, D' located side by side, balls E, E' contained in suitable retaining plates F, F', being located between each rider bar and its corresponding stationary track. Each rider bar and stationary track and balls and retaining plates therefor, are by preference similar to the construction shown and described in Patent No. 1,038,502, granted to me September 10, 1912. As far as above stated, the structure may be said to comprise therefore, a plurality of stationary tracks located side by side, each track supporting through the intermediary of the balls, a rider bar on which a corresponding door-half is mounted.

As the parts above referred to are identical on the opposite sides of the center line of the door, I have used the reference numerals and exponents to distinguish between the parts corresponding to the two door-halves.

Each of the stationary tracks D and D' is adjustably carried from the bracket C by means of the bolt and nut structures H. The rider bar B has secured thereto a rack J having teeth on its upper surface and located by preference midway of the two door halves, such rack being carried on a skirt K depending from the rider, while directly above the rack J, but separated therefrom by a suitable distance, is the corresponding rack L, the teeth of which face downwardly, and which is carried from, and adjustable vertically on the bracket C by the bolt and nut structure M. Between the racks J and L is located the pinion N, meshing with both of such racks, and connected to the rider bar B'. As stated this connection is made in such a manner, that the pinion is capable of vertical movement in respect to such rider bar, and this I prefer to accomplish by mounting the pinion on a stud O, carried on one end of a link P, the opposite end of which is pivoted to the rider bar B' so that such pinion is capable of vertical movement in respect to the rider bar. By this construction, it will be noted that with the fixed track D' properly adjusted, and the section A' properly adjusted in respect to its rider B', any desired adjustment may be made of the door section A without destroying the proper intermesh of the pinion N with the two racks.

J and L provided that with each adjustment of the door A, and consequent change of position of the rack J, the rack L be adjusted to maintain it at the fixed uniform distance from the rack J. This much simplifies the mounting of the doors of the character referred to.

It is obvious that with the general construction above described, a movement of 10 the door-half A' through a given distance in the direction of the arrows 1 and 2 Fig. 3, will move the pivot of the pinion N through the same distance and will give a movement twice as great to the rack J secured to the half A of the door, whereby the door-halves will be projected at a proper relative speed for each to close its respective share of the door opening when the part B' shall have reached its limit of movement and upon a 20 movement of the door-halves in the opposite direction to that shown by the arrows in Fig. 3, they will simultaneously each reach their open position.

Having thus described my invention, what

I claim and desire to secure by Letters Patent is:—

1. The combination with a plurality of fixed tracks, of a rider bar, and a traveling door part associated with each track; a fixed rack, a rack movable with one of the door parts; and a pinion mounted on another of the door parts, but movable relatively thereto transverse to the line of movement of the door parts, and engaging the said racks.

2. The combination with a plurality of fixed tracks, of a rider bar, and a traveling door part associated with each track; a fixed rack, a rack movable with one of the door parts; and a pinion engaging both of the said racks, and a link connection between 35 the pinion and the other door part.

In testimony whereof I have hereunto signed my name in the presence of two witnesses.

JAMES T. McCABE.

In the presence of—

FRED. SMYTH,

LOUIS CARQUE.
